UNITED STATES PATENT OFFICE

2,592,241

WHEEL DRESSING UNIT

Stanford P. Bruce, Detroit, Mich., assignor to
 Wheel Trueing Tool Company, Detroit, Mich.,
 a corporation of Delaware

Application April 23, 1949, Serial No. 89,289

3 Claims. (Cl. 125—11)

1

The present invention relates to a tool bracket, and more particularly to a tool bracket adapted to rotate a sprocket wheel by incremental amounts.

The description of the device of the present invention will be made in connection with a grinding wheel dressing assembly which has a rotatable tool holder carrying a diamond point therein for resurfacing or retrueing the periphery of a grinding wheel. A mechanism for trueing the surface of grinding wheels of this type has been described in my copending application Serial No. 744,749, filed April 29, 1947, entitled "Grinding Wheel Dressing Mechanism."

As described in my previously mentioned copending application, extended use of a diamond tool in the resurfacing or retrueing of a grinding wheel results in the production of flat surfaces on the diamond point. This results in the production of off-center ridges on the face of the diamond, causing the useful life of the diamond to be shortened, and impairing its efficiency as a dressing tool.

To overcome this difficulty, I have previously suggested providing a rotatable tool holder for the diamond tool, and means for rotating the tool holder and the diamond tool carried therein upon the completion of a traverse of the tool across the surface of a grinding wheel. Such incremental indexing of the diamond tool results in the production of a series of substantially flat triangular faces on the diamond tool which terminate at the true center of the diamond. Such periodic indexing operations not only increase the efficiency of the diamond tool as a dressing element, but also prolong the useful life of such dressing tools.

An object of the present invention is to provide a grinding wheel dressing assembly containing means for periodically rotating a dressing tool to present a new cutting face to the surface of the grinding wheel.

Another object of the present invention is to provide a tool bracket for periodically indexing a rotatable tool holder.

Another object of the present invention is to provide a tool bracket for the purposes mentioned above, which may be easily attached to the guard or bed of a conventional grinding machine, has a simple construction and is easy to manufacture.

Other objects of the present invention will be apparent from the following description of the attached sheet or drawings, in which:

Figure 1 is an elevational view of a grinding wheel dressing assembly illustrating the dressing

2

tool in working alignment with a grinding wheel, and illustrating one form of the tool bracket of the present invention;

Figure 2 is a sectional view taken substantially along the line II—II of Figure 1;

Figure 3 is an enlarged fragmentary view of the tool bracket illustrated in Figures 1 and 2, with a section broken away to show the interior construction;

Figure 4 is a perspective view of a grinding wheel dressing assembly illustrating another embodiment of a tool bracket;

Figure 5 is an enlarged fragmentary view of the tool bracket illustrated in Figure 4; and

Figure 6 is a cross-sectional view of the face of the tool bracket taken along line VI—VI of Figure 5.

As shown on the drawings:

Reference numeral 10 denotes in general a grinding wheel normally used on a center-type grinder. Enclosing at least a portion of the surface of the grinding wheel 10 is a conventional guard 11. A rotatable tool holder 12 carrying a diamond tool 13 is mounted for reciprocatory motion across the surface of the grinding wheel 10 parallel to the axis of the grinding wheel. The tool holder 12 is rotated by the rotation of a sprocket wheel 14 which is mounted about the periphery of the tool holder 12.

To provide periodic rotation of the sprocket wheel 14 and the diamond tool carried therein, a tool bracket 15 is provided. In the modification shown in Figure 1, the tool bracket 15 is attached to a surface of the guard 11 parallel to the plane of the grinding wheel 10 and is adapted to rotate the sprocket wheel 14 after the dressing tool has completed a traverse across the face of the grinding wheel. In some applications, it is desirable to attach the tool bracket to the bed of the grinding machine, rather than to the guard, especially where the guard may be moved out of position easily.

The tool bracket shown in Figures 1, 2 and 3 consists essentially of a rectangular shank portion 16 which is formed into a base portion 17 at its lower end. The shank portion 16 is secured to the guard 11 by means of bolts 18 and 19 which pass through slots 20 and 21 provided in the shank 16.

A pawl member 22 having a bifurcated portion forming ears 23 and 24 is pivotally mounted to the base 17 of the tool bracket 15 by means of a pair of pivot screws 25 and 26 which pass through the ears 23 and 24 and are rotatably held in the base 17. A pair of nuts 27 and 28 are provided

to anchor the pivot screws 25 and 26 within the ears 23 and 24.

A stop member, consisting of a generally rectangular plate 29 is removably secured to the base 17 by means of an Allen type screw 30. The stop 29 extends beneath the base 17 and serves to limit the pivotal movement of the pawl 22 about the base 17 of the tool bracket 15. The stop 29 thus holds the pawl 22 rigid when the sprocket wheel 14 is brought into contact with the same, thus enabling the sprocket wheel 14 to be rotated an incremental amount, but the pawl 22 is free to pass over the teeth of the sprocket wheel 14 when the dressing assembly is retracted for another pass across the surface of the grinding wheel 10.

As best seen in Figure 2, the base of the pawl member 22 has a beveled face 31 to facilitate the movement of the pawl member 22 over successive teeth of the sprocket wheel 14, when the dressing assembly is being retracted for another pass across the surface of the grinding wheel.

Another embodiment of the tool bracket of the invention is shown in Figures 4-6, inclusive. This embodiment may be used where a limited amount of space is available for the tool bracket and where it is desired to mount the tool bracket on the top portion of the guard assembly rather than at a side portion as shown in Figures 1-3.

Figure 4 illustrates a conventional grinding wheel 32 having its periphery surrounded by a guard 33. A tool holder 34 carrying a diamond point 35 is mounted for reciprocatory motion across the surface of the wheel 32, in the usual manner. A sprocket wheel 36 is secured to the tool holder 34 as a means for periodically rotating the same.

The tool bracket 37, as shown in Figure 4, consists of a generally cylindrical shank 38 which carries a collar 39 having an adjusting screw 40 therein for securing the collar 39 around any desired point along the axis of the shank 38. The collar 39 is secured to the guard 33 by means of screws 41 and 42 which pass through apertures provided in the collar 39 and are anchored to the guard 33. The base of the shank 38 is formed into flat portions 43 having a series of threaded apertures 44, 45 and 46.

A plate 47 having an elongated slot 48 is secured at any desired angle to the shank 38 by means of a locking bolt 49 which passes through the slot 48 and is threaded into one of the apertures 44-46.

A pawl member 50 having its top portion bifurcated into a pair of ears 51 and 52 is pivotally mounted to the base of the plate 47 by means of a pair of pivot screws 53 and 54 threaded into the ears 51 and 52 and held therein by means of locking nuts 56 and 57. A stop member consisting of a rectangular plate 58 is secured to a center portion of the base of the plate 47 and overlies the base of the plate 47. The stop member 58 is removably secured to the base of the plate 47 by means of an Allen type screw 59.

The base of the pawl member 50 has inclined face 55 to facilitate engaging successive teeth of the sprocket wheel 36.

The assembly shown in Figures 4-6 is also provided with a resilient assembly yieldably resisting movement of the pawl 50 when the pawl passes over successive teeth of the sprocket wheel 36. This resilient assembly contains a leaf spring 60 having a curved lip 61 spaced from the pawl 50 adapted to contact the same when the pawl 50 passes between successive teeth of the sprocket

wheel 36. Tension is applied to the leaf spring 60 by a second spring 62 which has a crimped portion 63 acting against the leaf spring 60 to hold the same against the plate 47. The springs 60 and 62 are secured to the shank 38 by means of a screw 64, carrying a washer 65, and threaded into the flat portion 43 of the shank 38.

From the foregoing it will be apparent that there is herein provided a tool bracket adapted to intermittently rotate a sprocket wheel by incremental amounts, the tool bracket being easily mounted upon a conventional grinding wheel dressing assembly and being easily manufactured from inexpensive materials.

It will, of course, be understood that various details of construction may be varied through a wide range without departing from the principles of this invention and it is, therefore, not the purpose to limit the patent granted hereon otherwise than necessitated by the scope of the appended claims.

I claim as my invention:

1. In combination with a grinding wheel dressing assembly having a rotatable tool holder carried by said assembly for translatory movement across the surface of a grinding wheel, said holder carrying a cutting tool therein arranged to periodically dress the surface of said grinding wheel, and a guard enclosing at least a portion of said wheel, means coacting with said holder at the completion of a traverse of said tool across the surface of said wheel to rotate said holder comprising a shank secured to said guard, a swingable member carried by said shank, and a stop member carried by said shank in the path of swinging movement of said swingable member for limiting the pivotal movement of said swingable member about said shank.
2. In combination with a grinding wheel dressing assembly having a rotatable tool holder carrying a cutting tool therein arranged to periodically dress the surface of a grinding wheel, a sprocket wheel carried by said holder for rotating the same, and a guard surrounding at least a portion of said wheel, means for rotating said holder at the completion of a traverse of said tool across the surface of said wheel comprising a shank secured to said guard, a swingable pawl member having a bifurcated portion carried by said shank, said pawl having a beveled edge for contacting successive teeth of said sprocket wheel, and a stop member carried by said shank in the path of swinging movement of said pawl member for limiting the swinging movement of said pawl about said shank.
3. In combination with a grinding wheel dressing assembly having a rotatable tool holder carrying a cutting tool therein adapted to periodically dress the surface of a grinding wheel, a sprocket wheel carried by said holder for rotating the same, and a guard surrounding at least a portion of said wheel, means for rotating said tool holder at the completion of a traverse of said tool across the periphery of said wheel comprising a shank secured to said guard, a swingable pawl member having its upper portion formed into a bifurcated portion pivotally carried by the end of said shank, and having a beveled edge for insertion between successive teeth of said sprocket wheel for rotating said sprocket wheel, and a stop member removably carried by said shank and overlying a portion of

said pawl to limit the pivotal movement of said pawl about the end of said shank.

STANFORD P. BRUCE.
